UNITED STATES PATENT OFFICE.

CHARLES ADOLPHE FONTAINE, OF PARIS, FRANCE.

COMBINED COMB AND HAIR CUTTER.

Application filed January 8, 1922. Serial No. 527,414.

To all whom it may concern:

Be it known that I, CHARLES ADOLPHE FONTAINE, a citizen of the French Republic, and resident of Paris, France, have invented certain new and useful Improvements in Combined Combs and Hair Cutters, of which the following is a specification.

My present invention relates to improvements in combined combs and hair-cutters of the type comprising a comb on which is fitted a stationary cutting blade to enable even an unskilled person to cut his hair or beard himself to the desired length without risk of hurting himself.

15 The object of my invention is to provide an improved device of the type mentioned, having simple but efficient means, whereby the cutting blade may be removably fixed to the comb.

20 A further object of my invention is to provide an improved device of the kind described, having a slide which is removably held on the comb and adapted to receive either an ordinary safety razor blade or a 25 profiled razor blade, having one cutting edge and a thicker opposite edge.

A still further object of my invention is to provide an improved device of the kind described, wherein the comb has a guiding 30 edge of substantially circular cross section for the reception of a correspondingly shaped yielding blade-carrier.

These and other objects of my invention are attained by the construction, arrangement and combination of parts, fully described and claimed hereinafter with reference to the accompanying drawings, wherein:

Fig. 1 is a side elevation of my improved 40 comb and hair-cutter.

Fig. 2 is a section on line A—B of Fig. 1;

Fig. 3 is a front elevation of the blade carrying slide removed from the comb.

Fig. 4 is a section on line C—D of Fig. 3.

45 Fig. 5 is a front view of the metal plate serving to secure the cutting blade to the slide.

Fig. 6 is a front view showing an alternative form of slide.

50 Fig. 7 is a cross section on line E—F of Fig. 6.

Fig. 8 is an end elevation of the parts shown in Fig. 6.

55 Fig. 9 is a front elevation of a modified form of slide, and

Fig. 10 is an edge view thereof.

Referring to the drawings, and more particularly to Figs. 1—5, 1 indicates the comb of special construction, provided on each side face with a shallow longitudinal groove 2. Slidably arranged on said comb is a slide 3, 4, made of a single piece and comprising a body portion 3 which yieldingly engages the longitudinal grooves 2 in the comb 1, and an outwardly projecting cheek 4 provided with three projections 6 at its lower part, for the reception of a usual safety razor blade having opposite cutting edges. Said razor blade is secured to the cheek 4 by means of a metal plate 5 (Fig. 5), provided with three openings in longitudinal line and two of which are made of ellipsoidal form with somewhat straight upper and lower rims, whilst the central opening is shaped to form one member of a bayonet joint.

The construction thus far described enables the razor blade to be rigidly fixed on the slide 3, 4, at the same time enabling the latter to slide longitudinally in both grooves 2 in the comb. The razor blade fixed to the slide 3 on one side of the comb enables the hair and beard to drop in accordance with the passage of the blade therethrough. The slide 3 may be arranged on the comb so that the cheek 4 thereof will be positioned either on the right or the left side of the comb, as desired.

In use the apparatus will be simply passed through the hair or beard to be cut. The latter will be cut to a more or less greater 90 length by having the slide secured over the coarse or the fine teeth of the comb.

Referring now to Figs. 6, 7 and 8, of the drawings, showing a slide designed to carry a razor blade with a single cutting edge, it 95 will be seen that the slide is provided with two lateral guide-members 7, between which the razor blade may be received. Engaged into each guide-member 7 is a small set-screw 8, by means of which the razor blade will 100 be adjusted and held in position. Secured to the side of each guide-member 7 by means of a rivet 9 is a spring 10, the upper end of which is bent substantially at right angles and engages the back of the razor blade 11 105 to hold the same in place.

It will be understood that the form of the blade-guide-members 7 and of the holding springs 10 may be modified as desired, and that other equivalent devices may be substi- 110

tuted for the set screws 8 without departing from the spirit of my invention.

In the constructions above described the comb has a guiding rim of substantially 5 square cross section, engaged by a correspondingly shaped portion of the blade carrying slide.

In the modification shown in Figs. 9 and 10 the slide 3', 4' is designed to receive either 10 an ordinary safety razor blade with two cutting edges or a razor blade with a single cutting edge, said blades being secured to said slide as already described.

The upper portion 3' of this modified slide 15 is bent on an arc of a circle as shown whereby a springy action is attained so that the slide will grip the back of a comb.

Having now fully described my said invention, what I claim and desire to secure 20 by Letters Patent, is:

1. The combination of a comb formed with longitudinal grooves on opposite sides thereof, a member slidably mounted on the comb having a body portion formed to extend around the back of the comb and fit 25 in said grooves, and a plate portion extending from the body portion at one side, offset from the comb at the upper end and engaging the teeth thereof near the lower ends, 30 and means for securing a razor blade to the outer side of the plate.

2. The combination of a comb formed with a longitudinal shouldered groove on each side, a holding member having a body 35 portion fitting over the back of the comb and formed with inwardly extending offset portions slidably engaging in said grooves, the

offsets thereof engaging the shouldered portions of the grooves, said member also having a plate portion extending downwardly 40 on one side of the comb and engaging the teeth thereof near the lower ends, and means for securing a blade to said plate portion having a cutting edge projecting below the lower edge of said plate portion, whereby 45 the body portion having the offsets engaging the shouldered portions of the comb will hold the plate portion against movement away from the comb.

3. The combination of a comb formed with a longitudinal shouldered groove on each side, a holding member having a body portion fitting over the back of the comb and formed with inwardly extending offset portions 50 slidably engaging in said grooves, the offsets thereof engaging the shouldered portions of the grooves, said member also having a plate portion extending downwardly from the body portion at one side of the comb and having an offset at the upper end 55 connecting it with the body portion, said plate portion engaging the teeth of the comb near the lower ends so that the plate is inclined with respect to the comb, and means for securing a blade on the outer face thereof with a cutting edge projecting below the plate portion, whereby the offset of the body portion engaging the shoulders formed in the comb will keep the lower edge of the 60 plate in contact with the teeth of the comb and the inclination of the plate to the comb will render the cutting edge of the blade 65 more effective.

CHARLES ADOLPHE FONTAINE.
